Patented Nov. 12, 1889.

UNITED STATES PATENT OFFICE.

WILLIAM M. PIATT, OF MAC-O-CHEEK, OHIO, ASSIGNOR OF ONE-THIRD TO
BENJAMIN P. RUNKLE, OF SAME PLACE.

GRAIN-BINDER.

SPECIFICATION forming part of Letters Patent No. 415,123, dated November 12, 1889.

Application filed August 16, 1887. Serial No. 247,088. (No model.)

To all whom it may concern:

Be it known that I, WILLIAM M. PIATT, a citizen of the United States, residing at Mac-o-cheek, in the county of Logan and State of Ohio, have invented Improvements in Grain-Binders, of which the following is a specification.

In order that my invention may be fully understood, I will proceed to describe it with reference to the accompanying drawings, forming part of this specification, in which—

Figure I is a plan of my main platform and binding mechanism. Fig I^a is a perspective view of a bearing-sleeve and clamping-nuts by which the brackets are secured together. Fig. II is a rear elevation. Figs. III, IV, and V are detail views of my curved needle or binder-arm, showing it in its upper, intermediate, and operative positions, respectively. Fig. VI is a side elevation of my reel. Fig. VII is a vertical section thereof on the line VII VII, Fig. VI, on a larger scale.

My improvements consist in the construction hereinafter described, and pointed out in the claims.

1 is the main frame, having the rollers 2 and main apron 3, supported on the rollers. The main apron is provided with series of teeth or brackets transverse thereof. Each tooth or bracket is made of metal of suitable kind and formed with a flat base 4 and projection 5, inclined backward, so that the teeth or brackets are enabled to forward the grain to the binder without dragging it. Where the projections are inclined forward they are found to force the grain unnecessarily. The base of each tooth or bracket is secured by rivets to the web of the apron, and if a thin web is employed a metal stay or plate 6 can be placed beneath the web.

7 is the binding-table; 8, the standard having the overhanging arm 9 and head 10.

11 is a needle-shaft, having crank-wheel 12, provided with wrist-pin 13, which forms the pivot for a curved needle 14, hinged thereto and working in the head of the standard. Secured to the head are a pair of brackets 15, extending across the binding-table and providing supports for the packer driving-shaft 18 and stationary rod 19 and ejector-shafts

26 and 27. The rod is secured fixedly to the bracket by clamp-nuts 19^a. Between the brackets and around the shafts 18, 26, and 27 are secured bearing-sleeves 16 by clamp-nuts 17. The bearing-sleeves and clamp-nuts 55 form means for uniting the brackets, and the bearing-sleeves provide journal-bearings for the shafts.

20 are rollers keyed to the driving-shaft 18, and 21 are rollers turning on the rod 19. Extending over the rollers are the upper aprons 22, provided with my improved rearwardly-inclined teeth 45. Hinged to the driving-shaft and extending over the binding-table are cut-off boards or wings 23. These wings 65 are raised to permit the passage of the incoming grain or lowered to prevent the ejectors from grasping the incoming grain by means of levers 24, hinged to the head of the standard and connected to plates 25 on the 70 wings.

26 is the inner ejector-shaft, and 27 the outer ejector-shaft. On these shafts are secured the cam-tracks 28, and on these shafts are mounted the sprocket-wheels 29, carrying endless chains 30, having ejector-fingers 31. The inner ejector-shaft has keyed to it cams 32, having grooves 33, in which travel studs 34 on the inner ends of the levers, providing means by which the levers are operated to move the wings. To cause the needle to move in the elliptical path indicated in dotted lines, I connect the middle portion of the needle with the outer ejector-shaft by means of a link 35, hinged to said shaft and 80 secured to a stud 36 on the needle. To assist the link in directing the needle, I provide, in addition thereto, a double link 37, connected to the rear side of the needle by means of a stud 38, and to a post 39, secured to one of the 90 brackets 15.

40 is the combined retaining-finger and compressor acting on one side of the bundle, while the needle acts as a compressor on the other side of the bundle.

41 is the trigger or trip-arm.

At the front end of the binding-table, arranged transversely thereof, is a spiral or screw conveyer 42, for adjusting the butts of the grain. This conveyer has a shaft 43, by 100

which it is journaled to the main frame. It is driven by a sprocket-wheel 44, connected by a chain 45 with a sprocket-wheel 46 on the main shaft 47 of the machine.

5 48 and 49 are notches or recesses in the table and cut-off boards or wings, respectively, for the passage of the teeth of the apron and belts.

50 48 and 49 are notches or recesses in the table and cut-off boards or wings, respectively, for the passage of the teeth of the apron and belts.

10 50 is the reel-shaft, having a circumferentially-grooved sleeve 51 moved thereon by a lever 52. The reel comprises a fixed hub 53, having arms 54, and loose hub 55, having arms 56, the arms carrying bats 57, loosely connected thereto. On the reel-shaft, between 15 the hubs, I secure adjustably, by means of a set-screw 59, the bracket 58, which is formed with arms 58^a and a projection 58^b. The latter forms a support for a rack 61, passing therethrough and sliding therein, and the 20 outer end of a rod 60 is connected to the rack 61 at one end and is connected at the other end to the sleeve 51. The arms of the bracket form supports for a worm-shaft 62, journaled in suitable bearings therein. The inner end 25 of the loose hub 55 is provided with a worm-wheel 63, with which the worm of the worm-shaft meshes, and the worm-shaft is provided with a pinion 64, rotated by the rack. These means provide an improved device for adjusting the position of the bats.

30 In Letters Patent No. 367,441, dated August 2, 1887, I have shown and described means for adjusting the reel-bats which do not permit sufficient play to the loosely-mounted reel-hub, as the crank and segment movement is very much limited, while in the present construction the movement is extensive. In the former construction the lever controlling the rack-segment has to be locked 35 while at rest to resist the pressure of the grain on the reel-bats, while in the present construction, by means of the worm-shaft and worm-wheel, the mechanism is self-locking, and the lever is not hampered with locking mechanism. In the present construction the outer hub is oscillated and the inner stationary hub is used as a guide for the connecting-rod.

35 The machine operates as follows: The grain is cut and reeled to the main apron, and by means of this apron and the upper aprons is packed into the space beneath the head and arm of the standard on the binding-table, the spiral or screw conveyer assisting the packing by adjusting the butts of the grain. When 45 enough grain has been forced onto the table,

the trigger throws the binding mechanism into gear, as described in Letters Patent No. 377,731, dated February 7, 1888, causing the wings to be depressed by the lever, so as to 60 keep the ejector-fingers from grasping any of the incoming grain during the binding operation. The needle at the same time advances its point and descends, dragging the grain as a compressor on the outer side, while the combined compressor and retaining-finger acts on the grain from the inner side. The tying and ejecting of the bundle are accomplished as in Letters Patent No. 384,072, dated June 5, 1888. 70

Having thus described my invention, the following is what I claim as new therein and desire to secure by Letters Patent:

1. The combination of the needle-shaft, crank-wheel having eccentric wrist-pin, the 75 curved needle hinged at its outer or upper end to the wrist-pin, the outer ejector-shaft, and the link-connection between the outer ejector-shaft and the middle portion of the needle, substantially as described. 80

2. The combination of the needle-shaft, crank-wheel having eccentric wrist-pin, the curved needle hinged at its outer or upper end to the wrist-pin, the outer ejector-shaft, the link-connection between the outer ejector-shaft and the middle portion of the needle, and the double link-connection between the packer-frame and the needle, substantially as described. 85

3. The combination, with the reel-shaft 50, 90 of the sliding grooved sleeve 51, the lever 52, engaging the sleeve, the inner hub 53, fixed to the reel-shaft, having arms 54, the outer sleeve or hub 55, loosely mounted on the reel-shaft, having arms 56, the bats 57, connected 95 to the arms, the worm-wheel 63, fixed to the inner end of the outer sleeve or hub, the bracket 58, having arms 58^a and projection 58^b, the worm-shaft 62, journaled in the arms, having its worm meshing with the worm-wheel, the gear-wheel 64, fixed to the worm-shaft, the rack 61, sliding in the projection and meshing with the gear-wheel, and the rod 60, connected at one end to the rack and at the other end to the sleeve, substantially as described. 100

WILLIAM M. PIATT.
